UNITED STATES PATENT OFFICE.

HARRY E. MORTON, OF BOSTON, MASSACHUSETTS.

VACUUM-BREAKER.

1,204,302.

Specification of Letters Patent.

Patented Nov. 7, 1916.

Application filed October 22, 1913, Serial No. 796,721. Renewed January 21, 1916. Serial No. 73,500.

To all whom it may concern:

Be it known that I, HARRY E. MORTON, a citizen of the United States, residing at Boston, in the county of Suffolk and State of Massachusetts, have invented an Improvement in Vacuum-Breakers, of which the following is a specification.

This invention relates to vacuum-breakers adapted to open the vacuum-space of a condenser to the atmosphere and thereby destroy the vacuum between a jet-condenser and a steam-engine, in case the condensing-water rises abnormally in the condenser, thereby to check its progress and prevent it from flowing back through the exhaust steam pipe to the engine and wrecking the engine.

In some particulars the invention is intended as an improvement upon the vacuum-breaker of my application #752,288, filed March 6, 1913, and involves the same principle of operation in that the weight of the condensing-water is utilized to cause the operation of the air-inlet valve to open the vacuum-space to the atmosphere, and destroy the vacuum. The vacuum-breaker of my aforesaid application is adapted to be arranged in upright position in a vertical portion of the exhaust steam-pipe or other part of the vacuum-space, whereas the present vacuum-breaker is adapted to be arranged on the outside of the condenser. In new installations it is usually possible to provide the exhaust steam-pipe with a vertical portion to receive the vacuum-breaker, although some object to extending the exhaust steam-pipe upward, but in old installations it is sometimes difficult to arrange the vacuum-breaker in the exhaust steam-pipe and occasionally an exhaust steam-pipe has no vertical portion in which the vacuum-breaker can be arranged, hence the desirability of arranging the vacuum-breaker on the condenser.

In the present embodiment of my invention, here shown for illustration, a receptacle is arranged at the outside of the condenser, which is closed to the atmosphere but is in open communication with the interior of the condenser to receive condensing-water which rises therein to an abnormal level, and which would flow back through the exhaust steam-pipe to the engine unless its progress was checked, said receptacle being movable by the weight of the condensing-water to control suitable means for oper-

ating an air inlet-valve to open the vacuum-space to the atmosphere and thereby destroy the vacuum and thus check the progress of the condensing-water, and prevent it from flowing back through the exhaust steam-pipe to the engine. Said receptacle may be pivotally supported and arranged for rotatable connection with the shell or case of the condenser, and is arranged so that a downward movement thereof is caused by the weight of the condensing-water which enters it. An air inlet-valve is provided for opening the vacuum-space to the atmosphere, and, as here shown, actuating means is provided for opening said valve, and tripping-mechanism is provided for the valve-actuating-means which is arranged between the actuating-means and the downwardly movable receptacle, and which is constructed and arranged to be operated upon a downward movement of said receptacle to permit operation of the valve-actuating-means. All of the component parts of the vacuum-breaker are or may be arranged on a supporting-plate which is arranged over a hole in the side wall of the condenser case, and which is bolted to said case, and said supporting-plate has an opening controlled by the air inlet-valve whereby to open the vacuum-space to the atmosphere and also has an opening by which communication may be permanently established between the interior of the condenser or vacuum-space thereof and the downwardly movable receptacle, so that the condensing-water may flow through said opening, and enter said receptacle and add its weight thereto to cause it to move downward.

Figure 1 is a front view of a jet-condenser, engine and exhaust steam-pipe, and a vacuum-breaker embodying this invention arranged on the outside of the condenser. Fig. 2 is an enlarged front view of the vacuum-breaker and its supporting-plate. Fig. 3 is a right hand side-elevation of the vacuum-breaker shown in Fig. 2. Fig. 4 is a vertical section of the vacuum-breaker shown in Fig. 2, taken on the dotted line 4-4. Fig. 5 is a sectional detail of a stop for the valve-actuating-lever. Fig. 6 is an enlarged front view of the vacuum-breaker, the parts being in the position they will occupy when the same has operated and the air inlet-valve has been opened.

10 represents the engine; 12 a jet-condenser; 13 a pump and 14 the exhaust steam-

pipe leading from the engine to the jet-condenser, and, so far as my present invention is concerned, said elements are or may be of any well-known or suitable construction. 5 The vacuum-breaker here shown is applied exteriorly to the side of the condenser, but its application is not limited to this particular part of the vacuum-space. In applying it to a condenser the shell or case of 10 the condenser has an opening at the side, see Fig. 4 above the normal level of the condensing-water which is adapted to be closed by a circular plate 20, arranged exteriorly on the shell and bolted thereto, 15 and said plate, as here shown, serves as a support for the component parts of the vacuum-breaker, which parts are arranged exteriorly thereon. Said plate, as here shown, has a hollow projection or boss 21, 20 arranged for open communication with the vacuum-space of the condenser, as for instance open communication is established through the opening in the side-wall of the condenser, and also through a pipe 75 which 25 is connected at one end with the end of the hollow boss 21, and at the other end with the exhaust steam-pipe 14, above the top of the condenser. Said boss has an opening at its upper side formed with a valve- 30 seat, adapted to receive any usual or suitable valve 22, designed to be opened outwardly and to be operated by means exteriorly disposed with respect to the condenser thereby to open the vacuum-space to the atmosphere 35 and destroy the vacuum. Said valve 22 has a stem 23, which is supported in upright position and guided by a bracket on the supporting-plate, and said stem has a hole 24 through it, transversely, to receive one end 40 of an actuating-lever 25, pivoted at 26, the other end of said lever bearing a heavy weight 27, which is designed, when permitted to fall by gravity to move said lever on its pivot to positively lift the valve from its 45 seat and thereby open the vacuum-space to the atmosphere. Said actuating-lever is held in position with its weighted end-portion elevated in readiness to fall, when permitted, by suitable tripping-mechanism 50 which is controlled by an operating-device, which latter is adapted to be operated by the weight of the condensing-water rising in the condenser when trouble occurs.

The operating-device which forms the essential novel element of the vacuum-breaker consists of a hollow receptacle 30, arranged in open communication with the interior of the condenser, but closed to the atmosphere, and, as here shown, said receptacle has a 60 hollow or tubular neck 31 at one end, preferably bent at right angles to the body portion to form an elbow, which has a conical end-portion 32 for engaging a correspondingly shaped seat 33, formed around the 65 edge of an opening 34 in the supporting-

plate 20, and has a trunnion opposite said end-portion arranged in a bearing in a bracket 36, on the supporting-plate; and said conical end-portion is held in firm engagement with its seat by a spring 35 arranged 70 on the trunnion between the neck and the bracket which spring acts expansively. When thus disposed the receptacle is pivotally supported on the outside of the supporting-plate and at the outside of the condenser, and is adapted to be rotated about a horizontal axis, the conical end-portion moving rotarily on the seat, and remaining in permanent engagement therewith. The receptacle normally occupies substantially 75 a horizontal position, as represented in Fig. 2, being held in such position by means hereinafter described, and is in open communication with the vacuum-space of the condenser, and in case the condensing-water 80 rises, as it will do when trouble occurs, said condensing-water will pass through the opening 34 in the supporting-plate and through the hollow neck and into the receptacle, and add its weight to the receptacle, tending to cause said receptacle to swing downward on its pivoted support. Thus it will be observed that downward movement of the receptacle is controlled by 85 the weight of the condensing-water which 90 rises in the condenser and enters the receptacle. Said downward movement of the receptacle is utilized to operate tripping-mechanism for the air inlet-valve, thereby 95 to permit said valve to open, to in turn open 100 the vacuum-space to the atmosphere and destroy the vacuum.

The receptacle is normally held in elevated position by a counter-weight 40, arranged on an arm 41, pivoted at 42, to a bracket 43 attached to the top of the receptacle, and said arm 41 normally rests on a fixed pin 44, extended laterally from an ear 45, on the supporting-plate 20, and said counter-weight is made solid and on account 105 of the leverage exerts a gravitating force sufficient to accomplish this result, but when said receptacle is filled or partially filled with condensing-water it overbalances the counter-weight 40, and said counter-weight 110 is lifted as the receptacle falls, and the arm 41 of the counter-weight slides along on the fixed pin 44, and, as here shown, passes by the pin.

In view of the fact that the weight of the receptacle is disposed at one side of its pivotal-support it is liable to swerve so that its conical end-portion will not remain correctly seated at all times, and by attaching a small counter-weight 70 to the receptacle, near its pivotal-support, this difficulty is overcome.

The tripping-mechanism for the air inlet-valve is arranged in coöperative relation with the receptacle 30, and, as here shown, said tripping-mechanism comprises a bell- 125 130

crank lever, pivoted at 50 to an ear 51 on the supporting-plate 20, one arm of which, as 52, engages a pin 53, extended laterally from the lever 25, and the other arm of 5 which, as 54, is extended downward and bears a pin 55, which is extended laterally from its lower end-portion and enters a notch 56 formed in the top of bracket 43, which is attached to the top of the receptacle 30. Normally, the pin 55 occupies a position in the notch 56, so that the bell-crank lever is held in fixed position, and when so held the arm 52 of said bell-crank lever holds the actuating-lever 25 of the air inlet-valve in 10 elevated position. Upon a downward movement of the receptacle 30 the pin 55 is disengaged and the bell-crank lever is released, and being free to move on its pivot 50, will be so moved by the weight of the actuating-lever 25, thus permitting said actuating-lever to move on its pivot 26 and positively open the air inlet-valve.

To limit downward movement of the receptacle, a slotted link 60 may be employed, 25 which is loosely connected at its lower end to the bracket 43 on the receptacle, and its slotted portion engages the pin 53 on the actuating-lever 25, so that downward movement of both the receptacle and actuating-lever is limited. The actuating-lever falls until it strikes a yielding stop 65 on a projection 66, extended laterally from the ear 45 on the supporting-plate, or in lieu thereof any other form of stop may be provided for 35 limiting the downward movement of said actuating-lever. After the vacuum-breaker operates the parts thereof will be restored by hand at the convenience of the engineer, the co-operative parts of the tripping-mechanism being reset and the receptacle and 40 valve actuating-lever restored to normal elevated position, and the condensing-water contained in the receptacle is caused to flow back to the condenser, and being of small 45 volume the receptacle is quickly emptied.

I claim:—

1. The combination with a jet-condenser, 50 of a vacuum-breaker having an air inlet-valve arranged to open the vacuum-space to the atmosphere thereby to destroy the vacuum, a movable receptacle arranged at the outside of the condenser which is closed to the atmosphere and is in open communication with the vacuum-space, to receive condensing-water which rises in the condenser, and by its weight causes the receptacle to 55 move downward, and means controlled by said receptacle, upon a downward movement thereof, to operate said air inlet-valve to open the vacuum-space, substantially as described.

2. The combination with a jet-condenser, 60 of a vacuum-breaker having an air inlet-valve arranged to open the vacuum-space to the atmosphere thereby to destroy the vacu-

um, a hollow, pivotally supported receptacle arranged at the outside of the condenser which is closed to the atmosphere and is in open communication with the vacuum-space, to receive condensing-water which rises in 70 the condenser, the weight of which moves said receptacle downward, and means controlled by said receptacle upon a downward movement thereof to operate said air inlet-valve to open the vacuum-space, substantially 75 as described.

3. The combination with a jet-condenser, of a vacuum-breaker having an air inlet-valve arranged to open the vacuum-space to the atmosphere and thereby destroy the 80 vacuum, a weighted actuating-lever for said valve, tripping-mechanism controlling the movement of said actuating-lever, and a receptacle with which said tripping-mechanism is associated, which is arranged at the 85 outside of the condenser and is closed to the atmosphere and is in open communication with the vacuum-space, to receive condensing-water which rises in the condenser and by its weight causes the receptacle to move 90 downward to control the operation of said tripping-mechanism, substantially as described.

4. The combination with a jet-condenser, of a vacuum-breaker having an air inlet- 95 valve arranged to open the vacuum-space to the atmosphere thereby to destroy the vacuum, a hollow receptacle rotatably connected with the condenser opposite the vacuum-space thereof which is in open communication with the interior of the condenser and is closed to the atmosphere and is adapted to receive condensing-water which rises in the condenser, means to hold said receptacle in elevated position, arranged for operation 100 by the weight of the condensing-water which enters the receptacle, permitting said receptacle to swing downward, and means controlled by and upon a downward swinging motion of the receptacle to operate the 105 air inlet-valve to open the vacuum-space, substantially as described.

5. The combination with a jet-condenser, of a vacuum-breaker having an air inlet-valve arranged to open the vacuum-space to 110 the atmosphere thereby to destroy the vacuum, actuating-means for said valve, tripping-mechanism for said actuating-means, a hollow receptacle rotatably connected with the condenser opposite the vacuum-space 115 thereof, which is in open communication with the interior of the condenser and is closed to the atmosphere and is adapted to receive condensing-water which rises in the condenser, means to hold said receptacle in 120 elevated position arranged for operation by the weight of the condensing-water which enters the receptacle, permitting said receptacle to swing downward, and means controlled by and upon a downward swinging 125 130

movement of the receptacle to disengage the tripping-mechanism and permit operation of the actuating-means for the air inlet-valve, substantially as described.

5 6. The combination with a jet-condenser having an opening in its side, a plate closing said opening, an air inlet-valve arranged on said plate to open the vacuum-space to the atmosphere thereby to destroy the vacuum, 70
10 a movable receptacle arranged on said plate which is closed to the atmosphere and is in open communication with the vacuum-space, to receive condensing-water which rises in the condenser and by its weight causes the 75
15 receptacle to move downward, and means controlled by said receptacle upon downward movement thereof to operate said air inlet-valve to open the vacuum-space, substantially as described.

20 7. The combination with a jet-condenser having an opening in its side, a closure for said opening, an air inlet-valve arranged on said closure to open the vacuum-space to the atmosphere thereby to destroy the vacuum, 80
25 said closure having a hole through it arranged to form a seat, a receptacle pivotally supported on said closure which is closed to the atmosphere and has a hollow neck with an end-portion arranged to engage said seat, 85
30 whereby said receptacle is in open communication with the vacuum-space, to receive condensing-water which rises in the condenser and by its weight causes the receptacle to swing downward, and means controlled by 90
35 said receptacle upon a downward swinging movement thereof to operate said air inlet-valve to open the vacuum-space, substantially as described.

8. The combination with a jet-condenser 40 having an opening in its side, a closure for said opening, an air inlet-valve arranged on said closure to open the vacuum-space to the atmosphere thereby to destroy the vacuum, said closure having a hole through it arranged to form a seat, a receptacle pivotally 105
45 supported on said closure which is closed to the atmosphere and has a hollow neck with an end-portion arranged to engage said seat, whereby said receptacle is in open communication with the vacuum-space, to receive condensing-water which rises in the condenser and by its weight causes the receptacle to swing downward, means to hold said neck in permanent engagement with the 110
50 seat, but permitting rotary movement thereof, and means controlled by said receptacle upon a downward swinging movement thereof to operate said air inlet-valve to open the vacuum-space, substantially as described.

55 9. The combination with a jet-condenser having an opening in its side, a closure for said opening, an air inlet-valve arranged on said closure to open the vacuum-space 115
60 to the atmosphere thereby to destroy the

vacuum, said closure having a hole through it arranged to form a seat, a receptacle pivotally supported on said closure which is closed to the atmosphere and has a hollow neck with an end-portion arranged 70
75 to engage said seat, whereby said receptacle is in open communication with the vacuum-space, to receive condensing-water which rises in the condenser and by its weight causes the receptacle to swing downward, means to hold said receptacle in elevated position adapted to be overbalanced by the weight of the condensing-water which enters the receptacle, and means controlled by 80
85 said receptacle upon a downward swinging movement thereof to operate said air inlet-valve to open the vacuum-space, substantially as described.

10. The combination with a jet-condenser having two openings opposite the vacuum-space thereof, an air inlet-valve normally closing one of said openings arranged when open to open the vacuum-space to the atmosphere and thereby destroy the vacuum, a hollow receptacle arranged in front of the other opening and having a rotatable connection with the condenser at such point, whereby it is in open communication with the interior of the condenser but is closed to the atmosphere and is adapted to swing 95
90 about a horizontal axis, means to hold said receptacle in elevated position adapted to be overbalanced by the weight of the condensing-water which enters the receptacle, and means controlled by said receptacle and upon downward movement thereof to operate said air inlet-valve to open the vacuum-space, substantially as described.

11. The combination with a jet-condenser, of a vacuum-breaker having an air inlet-valve arranged to open the vacuum-space to the atmosphere and thereby destroy the vacuum, a hollow receptacle closed to the atmosphere and having a neck with an end-portion rotarily engaging a seat so disposed that said receptacle is in open communication with the vacuum-space and is adapted to receive condensing-water which rises in the condenser and by its weight causes the receptacle to move downward, said receptacle, upon a downward movement thereof, controlling the operation of the air inlet-valve, substantially as described.

12. The combination with a jet-condenser, of a vacuum-breaker having an air-inlet valve arranged to open the vacuum-space to the atmosphere thereby to destroy the vacuum, a movable receptacle arranged at the outside of the condenser which is closed to the atmosphere and is in open communication with the vacuum-space to receive condensing-water which rises in the condenser, and by the weight thereof is moved downward, counter-balancing means arranged to hold the receptacle in elevated 120
125
130

position which is adapted to be overcome by the weight of the condensing-water which enters the receptacle, and means controlled by said receptacle, when in elevated 5 position, to hold the air-inlet valve in closed position, which permits the valve to open when the receptacle moves downward, substantially as described.

13. The combination with a jet-condenser, 10 of a vacuum-breaker having an air-inlet valve arranged to open the vacuum-space to the atmosphere and thereby destroy the vacuum, a movable receptacle arranged at the outside of the condenser 15 which is closed to the atmosphere, and is in open communication with the vacuum-space which receives condensing-water which rises in the condenser, counter-balancing means for holding said receptacle in elevated 20 position adapted to be overcome by the weight of the condensing-water which enters the receptacle, means engaged by said receptacle when in elevated position for holding the air-inlet valve in closed 25 position which is adapted to be disengaged when the receptacle moves downward, permitting operating of the air-inlet valve to open the vacuum-space, and means to limit downward movement of the receptacle, substantially 30 as described.

14. The combination with a jet-condenser, of a vacuum-breaker having an air-inlet valve arranged to open the vacuum-space to the atmosphere and thereby destroy the vacuum, a weighted actuating-lever for said valve, tripping-mechanism controlling the movement of said lever, and a receptacle arranged for engagement with said tripping-mechanism, which is arranged 40 at the outside of the condenser and is closed to the atmosphere and is in open communication with the vacuum-space to receive condensing-water which rises in the condenser, and by its weight causes the receptacle to move downward to disengage the tripping-mechanism and permit operation of the air-inlet valve, said receptacle being subsequently restored to engaging 45 position by hand, substantially as described.

15. The combination with a jet-condenser, 50 of a vacuum-breaker having an air-inlet valve arranged to open the vacuum-space to the atmosphere and thereby destroy the vacuum, a weighted actuating-lever for said valve, tripping-mechanism controlling the movement of said lever, and a receptacle arranged for engagement with said tripping-mechanism which is arranged 55 at the outside of the condenser and is closed to the atmosphere, and is in open communication with the vacuum-space to receive condensing-water which rises in the con-

denser, and by its weight causes the receptacle to move downward to disengage the tripping-mechanism and permit operation 65 of the air-inlet valve, means to limit downward movement of the valve actuating-lever, and means to limit downward movement of the receptacle, said actuating-lever and receptacle being subsequently restored 70 to engaging position with the tripping-mechanism by hand, substantially as described.

16. The combination with a jet condenser having an opening in its side wall above 75 the normal level of the condensing-water therein, of a vacuum-breaker connected with said condenser at said opening comprising a hollow supporting-member, a pipe connecting said member with the exhaust steam-pipe above the condenser, an air-inlet valve arranged on said member to open the vacuum-space to the atmosphere, a receptacle pivotally supported on said member which is closed to the atmosphere and 80 is in open communication with the vacuum-space to receive condensing-water which rises in the condenser, and by its weight causes the receptacle to move downward, and means controlled by said receptacle 85 upon a downward movement thereof to operate said air-inlet valve to open the vacuum-space, substantially as described.

17. The combination with a jet-condenser, 95 of a vacuum-breaker having an air-inlet valve arranged to open the vacuum-space to the atmosphere, and thereby destroy the vacuum, a weighted actuating-lever for said valve, tripping-mechanism controlling the movement of said actuating-lever, and a receptacle arranged at the outside of the condenser, which is closed to the atmosphere and is in open communication with the vacuum-space to receive condensing-water which rises in the condenser and by its 100 weight causes the receptacle to move downwardly, said receptacle having engaging-means adapted for engagement with the tripping-mechanism, thereby to hold said tripping-mechanism in position to hold the 105 actuating-lever with the air-inlet valve closed, and when the receptacle is swung downward by the weight of the condensing-water, to disengage said tripping-mechanism and permit movement of said actuating-lever to open the air-inlet valve, substantially 110 as described.

In testimony whereof, I have signed my name to this specification, in the presence of two subscribing witnesses.

HARRY E. MORTON.
